Primary Examiner — Daniel J Domino*(74) Attorney, Agent, or Firm* — Lee & Hayes, P.C.(57) **CLAIM**

The ornamental design for a display screen with graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a first embodiment of a display screen with graphical user interface; and,

FIG. 2 is a front view of a second embodiment of a display screen with graphical user interface.

The broken lines showing a display screen and elements of the graphical user interface illustrate portions of the article, and form no part of the claimed design. The dot-dash broken line shown in FIG. 2 illustrates a boundary, and forms no part of the claimed design.
